UNITED STATES PATENT OFFICE

ANDREW LOVE, OF PADDINGTON, NEW SOUTH WALES, AUSTRALIA

SHOE FASTENING

Application filed June 10, 1932. Serial No. 616,553.

This invention relates to shoe fasteners of the type forming the subject of United States Patent No. 1,741,640, and it consists in certain improvements with the object of rendering the fastening adjustable so that it may be adapted to shoes of various sizes, or, more correctly, to shoes in which the distances between the top and bottom eyelets are various. In the previously patented fastenings the rods had to be made in various lengths to suit different shoes, but in the improved fastening the rods are adjustable as regards length and therefore may, within limits, be adapted to suit different shoes.

Another improvement is in regard to the means for anchoring the elastic members which are now individually equipped with anchoring means each of which consists of a small clip formed of a flat metal plate with a lateral lug turned over to securely grip the elastic member.

To fully describe and ascertain the invention reference is now made to the accompanying drawing depicting a preferred construction embodying the invention.

In the drawing

Fig. 1 is a perspective view showing portion of a shoe fitted with the improved fastening, the latter being closed,

Fig. 2 is a front elevation showing the fastening open;

Fig. 3 is a perspective view showing the two bars of one fastening in open arrangement;

Fig. 4 illustrates one of the elastic members with attached anchoring means;

Fig. 5 is a sectional elevation of the device shown in Fig. 4 and

Fig. 6 is a sectional elevation showing portion of a shoe front, an eyelet therein, an elastic loop with anchoring means fitted in said eyelet and one of the rod-members passed through said loop.

The shoe 7 has the usual frontal opening 8 and on either side thereof eyelets 9, 9. The fastening consists of a pair of extensible rods indicated generally in Figs. 1, 2 and 6 by reference numeral 10, and a plurality of rubber loops (such as 11) for connecting

one of said rods to the eyelets in one side of a shoe front, and the other rod to eyelets in the other side of the shoe front.

The rods, as clearly shown in Fig. 3 each consists of two main parts 10¹ and 10², the part 10¹ being tubular and the part 10² being slidable telescopically in the part 10¹. This construction enables the rods to be adjusted as to length for the purpose hereinbefore stated.

One of the parts 10² is terminally formed with an offset eye 12, and the other with a hook 13 adapted to engage the eye 12 to constitute a loose hinge connection permitting partial rotation or planar displacement of one rod in relation to the other.

To limit the approach of the parts 10¹ to the hinge and to thus avoid jamming, the parts 10² are formed with inwardly projecting stop-lugs 14.

At the upper end of each part 10¹ there is affixed an offset lug 15 which serves as a finger grip to facilitate manipulation of the fastening when fitted to a shoe as in Fig. 1. One of these lugs 15 is formed with an eye 16 (for uniformity both are preferably so formed) adapted to receive and releasably retain a hook member 17 projecting from the other lug 15.

The rubber loops 11 are each secured to an anchor plate 18 of thin metal originally of T shape but with the stem of the T turned over to form a hook 19 which engages the loop—see Figs 4 and 5.

In fitting the fastening to a shoe, the loops 11 are drawn through the eyelets from the inside until the plates 18 lie snugly against the inner face of the shoe front as shown in Fig. 6, the hooks 19 entering the eyelets. One of the rods 10 is threaded through the loops on one side and the other rod through the loops on the other side, the hinge connection being then made by passing the terminal hook 13 on one rod through the eye 12 on the other. The parts are then as shown in Fig. 2. To close the fastening the finger grips 15 are then drawn together and the hook 17 passed through the eye 16 as shown in Fig. 1.

What I claim and desire to secure by Letters Patent is:

Shoe fastening means, comprising a pair of metal rods each consisting of a tubular part and a solid part slidably in the tubular part, said rods being loosely hinged together at one end and equipped with means for mutually and releasably engaging their

other ends, stop lugs limiting the length adjustability of the rods in one direction, and a plurality of elastic members for connecting one of said rods to eyelets in one side of a shoe front and the other rod to eyelets in the other side of the shoe front. 70

ANDREW LOVE.
